PROCESS FOR SEPARATING ALKYL PHENOLS

Daniel B. Luten, Jr., and Aldo De Benedictis, Berkeley, Calif., assignors to Shell Development Company, San Francisco, Calif., a corporation of Delaware

Application July 15, 1941, Serial No. 402,490

2 Claims. (Cl. 260—621)

The present invention relates to a process for the separation of alkyl phenols. More particularly it relates to a process wherein mixtures of alkyl phenols are sulfonated to form sulfonic acids which are selectively decomposed and separated.

In the past it has been proposed to separate mixtures of alkyl phenols by the so-called Brückner process, in which a mixture of these compounds is treated with sulfuric acid under conditions to form alkyl phenol mono-sulfonic acids. The acids so formed are diluted with water and the resulting mixture is steam distilled. As the sulfonic acids hydrolyze to regenerate the original phenols, the latter are vaporized with the steam and pass overhead. Thus, those alkyl phenols which decompose most readily pass overhead first, while the more stable phenols pass overhead only after the mixture is allowed to come to a higher temperature for the hydrolysis of the corresponding sulfonic acids. This temperature is regulated by controlling the amount of water in the boiling mixture.

It is an object of our invention to improve the Brückner process. It is a further object to carry out a process which is capable of giving sharper separations than known processes based partially upon the foregoing principle. It is another object to carry out a process without the consumption of large quantities of steam heretofore required. Still further objects will become apparent from reading the following specification.

Our invention comprises subjecting a mixture of alkyl phenols to the action of sulfuric acid or other sulfonating agent, such as chlorosulfonic acid, etc., under conditions to form predominantly monosulfonic acids with phenols, and separating the monosulfonic acids formed from free phenols with the aid of a stable water-immiscible solvent in which the sulfonic acids and the phenols are soluble. We may operate in such a manner that substantially all of the phenols are monosulfonated, or we may prefer to sulfonate only a portion of the phenols in the original mixture to form monosulfonic acids. In the former case we fractionally hydrolyze the resulting totally sulfonated product, preferably in the presence of a stable water-immiscible solvent for phenols, which may later be used in separating phenols from residual monosulfonic acids. In case we operate to sulfonate only a portion of the phenols, we prefer to separate the sulfonated phenols from any un-sulfo-

nated residue by means of solvent prior to hydrolysis, partial or otherwise, of the phenol monosulfonic acids.

In cases where we sulfonate substantially all of the initial mixture, our process usually involves the following steps: (1) sulfonating the mixture; (2) diluting the reaction mixture so formed with water, and preferably adding solvent; (3) maintaining the resulting reaction mixture at conditions of acidity, concentration and temperature favorable to hydrolysis until the optimum amount of least stable sulfonic acids has hydrolyzed; (4) subjecting the reaction mixture containing free phenols and unhydrolyzed sulfonic acids to extraction with organic solvent to produce a first phenolic fraction and residual unhydrolyzed sulfonic acids; (5) adjusting the conditions to favor further hydrolysis of the residual mixture by the adjustment of water and/or acid concentration and/or increasing the temperature of the mixture, etc., to effect further hydrolysis of the residual portion of the sulfonic acids; and (6) subjecting the resulting mixture containing a second quantity of free phenols to a second solvent extraction with an organic solvent to remove the second quantity of phenols and repeating the above operation until the desired number of phenolic fractions has been separated.

In cases where we operate to sulfonate only a portion of the initial mixture, the steps are generally as follows: (1) the mixture is partially sulfonated; (2) the resulting product, preferably in the presence of water, is treated with solvent to separate free phenols to produce a solvent phase containing dissolved free phenols and a residual monosulfonic acid phase as a first product; (3) the solvent is separated from said free phenols; (4) said free phenols are further partially sulfonated; (5) the resulting mixture is treated with solvent to produce a second residual sulfonic acid layer as a second product and a solvent layer containing phenols; and (6) the above steps are repeated until the desired number of sulfonic acid fractions has been produced. The sulfonic acid fractions are hydrolyzed to regenerate the corresponding free phenols.

Our separation depends upon the different tendencies toward hydrolysis which the various alkyl phenol sulfonic acids exhibit under different conditions for hydrolysis, as well as their tendencies to be sulfonated at different rates under different conditions of sulfonation. This

latter will be discussed at length hereinafter. This tendency to hydrolyze depends upon a number of factors, the more important of which are the structure of the alkyl phenol sulfonic acid, the temperature, and the nature of the hydrolytic medium. This latter is a complex function of the concentration of acid, the concentration of water, the amount of undissociated sulfonic acid present, the dielectric properties of the medium, etc. Also, a given temperature increase may increase the velocity of hydrolysis more for one sulfonic acid than another. We have found that, in general, for any given alkyl phenol sulfonic acid there exists an optimum set of conditions for hydrolysis. Our invention is based upon the maintenance of the sulfonic acid mixture under conditions of hydrolysis such that principally only one or a particular group of sulfonic acids hydrolyzes, then separating the corresponding alkyl phenol, changing the hydrolytic conditions of the residual unhydrolyzed sulfonic acids to favor the hydrolysis of some other sulfonic acid or group of acids, separating these and continuing as above until the desired degree of separation is attained.

We have found that the most convenient way to adjust the hydrolytic conditions is to vary the temperature and the acid concentration of the mixture to be hydrolyzed, the latter factor including adjusting the concentration of the sulfonic acids themselves. This is accomplished by carrying out the hydrolysis in vessels in which the heat input can be controlled, as by steam coils, jacketing and the like, and by adjusting the acid concentration of the mixture by the addition and/or evaporation of water or the addition of acid.

Our invention can be better understood from the figures, which represent different embodiments thereof.

Figure I is a flow diagram representing the batch method for carrying out our process. Agitator 1 is a vessel equipped with stirrer 2 run by motor 3, and heating coil 4, as well as offtake manifold comprising valves 5 to 10, is adapted to stand elevated pressures and is provided with safety valve 11.

In the first stage of operation, valves 5—10 and 12 are closed and valves 13 and 14 are opened, charging agitator 1 with the proper quantities of alkyl phenols and sulfuric acid, respectively. Stirrer 2 is started and the sulfonation allowed to proceed until substantially all of the phenols have been sulfonated. If desired, this reaction rate may be increased or the type of sulfonation altered, as explained below, by increasing the temperature by means of coil 4.

When the phenols are sulfonated to the desired degree, the conditions for partial hydrolysis of the sulfonic acids are adjusted as desired by admitting sulfuric acid and/or water by valves 14 and 15, respectively. A substantially water-immiscible solvent for phenols, such as benzene, is run into agitator 1 via valve 16 for the reasons discussed below. The temperature is regulated by means of coil 4 for optimum hydrolysis. When the sulfonic acids have hydrolyzed to the desired degree and the system has come to equilibrium with respect to the solvent, stirrer 2 is stopped and the mixture allowed to separate into two phases, an upper solvent phase containing dissolved phenols and a lower aqueous phase containing sulfuric acid and unhydrolyzed sulfonic acids. Valve 17 is closed and the upper solvent phase is withdrawn through the proper valve in

the manifold system and passes thence to tank 19. A portion of fresh solvent is then admitted to agitator 1 through valve 16. The stirrer 2 is started and the mixture caused to come to equilibrium. Stirrer 2 is stopped and the phases allowed to separate. The upper phase may then be withdrawn through the proper valve of the manifold system and allowed to pass to tank 19. Then the extraction may be repeated until the required degree of separation of free phenols from sulfonic acids is attained. After the separation of two phases after the addition of the last portion of solvent, valves 20, 21 and 22 are closed and valves 12 and 23 are opened allowing the bottom phase to pass through line 24 to sulfonic acid storage tank 29.

If desired, the acidity of the residual unhydrolyzed sulfonic acid can be increased by closing valve 23 and passing the lower phase through evaporator 25 equipped with heating coil 26. A portion of water may then be evaporated, passing out through line 27. After sufficient water has been evaporated, valve 28 is opened and the concentrated sulfonic acid solution is passed through line 24 to tank 29.

When all of the lower phase has passed from agitator 1, valves 21 and 23 are closed and valves 12 and 20 are opened. This admits the last solvent portion to tank 19. The solvent and phenols are passed from tank 19 through valve 17 to distillation column 18 equipped with reboiler 30 and partial condenser 31. In column 18 the solvent is separated from the phenols which latter are withdrawn from the bottom of still 27 through valve 32 and passed to storage not shown, while solvent passes off the top of still 18 through line 33 to condenser 34, thence to solvent tank 35 for use in another cycle.

In stage II the cycle is repeated further separating the unhydrolyzed sulfonic acids. Valve 36 is opened and sulfonic acids from tank 29 are charged to agitator 1. The acidity of the mixture in agitator 1 is adjusted by the addition of acid and/or water through valves 14 and 15, respectively. In this hydrolysis, the conditions are adjusted to favor the hydrolysis of a second portion of the residual unhydrolyzed sulfonic acids to form a second phenolic fraction. The above cycle is then repeated and the still more difficultly hydrolyzable sulfonic acids hydrolyzed until the required number of phenolic fractions has been separated. At the end of the process sulfuric acid may be withdrawn from the system through draw-off valve 22.

Figure II is a flow diagram representing a continuous method for carrying out our process. Sulfuric acid and alkyl phenols are continuously admitted to reactor 50 wherein monosulfonic acids are formed which feed continuously hydrolyzer 51 to which water and preferably a portion of solvent are admitted. The mixture leaving hydrolyzer 51 contains sulfonic acids and unhydrolyzed phenols, which pass to extractor 52, wherein they are contacted with a further quantity of solvent. The solvent selectively dissolves the phenols and the extract phase so formed passes to distillation column 53 wherein phenol fraction #1 is separated from solvent, which latter is returned for use in another cycle. The raffinate containing unhydrolyzed sulfonic acids passes to evaporator 54 wherein the acidity of the solution is increased. From evaporator 54 the mixture passes to hydrolyzer 55 to which preferably a portion of solvent may be added and also sulfuric acid. The increased acidity affects the equilib-

rium to cause the still more difficultly hydrolyzable sulfonic acids to yield the corresponding phenols. If desired, evaporator 54 may be bypassed or more water may be added. The temperature in evaporator 54 is maintained to favor further hydrolysis of sulfonic acids. The reaction mixture passes thence to extractor 56 wherein the mixture is contacted with solvent to form raffinate and extract phases which are treated as in the preceding section to yield those phenols containing the components more difficultly hydrolyzable than those from which phenolic fraction #1 was derived. The raffinate containing still more difficultly hydrolyzable sulfonic acids passes to evaporator 58 wherein the acidity is increased by further evaporation and/or by the addition of further quantities of sulfuric acid, thence to hydrolyzer 50. The reaction mixture passes to extractor 60 wherein it is contacted with solvent to form further raffinate and extract phases, the latter of which is separated in distillation column 61 and thus the foregoing cycle is continuously repeated in subsequent units comprising hydrolyzers, evaporators, etc., as often as desired to attain the required degree of fractionation.

Figure III is a flow diagram representing a continuous method for carrying out our process wherein the initial mixture is only partially sulfonated. Sulfuric acid and alkyl phenols are continuously admitted to reactor 70 wherein monosulfonic acids are formed which are fed continuously to extractor 76, preferably with the addition of water. Solvent is continuously admitted to extractor 76. This solvent selectively dissolves unreacted phenols and the extract phase so formed passes to distillation column 72 wherein the unreacted phenolic residue is separated from the solvent, which is returned for use in another cycle. The raffinate from extractor 76 comprises unhydrolyzed sulfonic acids which may be hydrolyzed to produce phenolic fraction 1'. The phenol residue is treated with further quantities of sulfuric acid in reactor 78 under conditions to sulfonate a further quantity of the phenols. The resulting mixture is extracted in extractor 74 with solvent and separated from solvent in distillation column 75, as described hereinbefore, to produce a second fraction of unhydrolyzed sulfonic acids which may be hydrolyzed to regenerate phenolic fraction 2', as well as a phenol residue. The latter is passed to reactor 76 wherein it contacts further quantities of sulfuric acid to produce another mixture comprising sulfonic acid and free phenols. This preferably with the addition of water passes to extractor 77 wherein it is separated by solvent, forming a third unhydrolyzed sulfonic acid residue which may be used to regenerate phenolic fraction 3' by hydrolysis. The phenolic fraction may be separated from the solvent in distillation column 78.

Our process is applicable to the separation of mixtures of alkyl phenols derived from different sources such as petroleum, coal tar, etc. Although we prefer to employ mixtures of substantially pure phenols, we can apply our process to alkyl phenol mixtures diluted with inert hydrocarbons.

In general, the sulfonation may be carried out at temperatures between 0° C. and 250° C., but in general we prefer to operate at temperatures not greater than about 150° C. because the tendency of sulfuric acid to oxidize the phenols at higher temperatures. The amount of sulfonating agent employed ranges from below 1 to about

5 equivalents of sulfonating agent per equivalent of alkyl phenol. However, in general, we prefer to employ 3 or less equivalents of sulfonating agent because of the subsequent dilution and re-concentration that would be required in subsequent separations if a large excess of agent were employed. Although other sulfonating agents may be used, we prefer concentrated sulfuric acid because of its cheapness and ready availability.

10 The initial sulfonation step may be carried out under such conditions of temperature, concentration and time that substantially all of the phenols present in the mixture are sulfonated, or, it may be done in such a manner that only part of the mixture is sulfonated. However, in either case we prefer to operate so that monosulfonic acids are the principal product.

15 It is known that the type of sulfonation, that is, the position in the molecule which the sulfonic acid group takes, is among other things a function of temperature. In other words, a given phenol at a low sulfonation temperature might yield a para-sulfonic acid, while the same phenol at a higher temperature of sulfonation might yield an ortho-sulfonic acid. The different type sulfonic acids hydrolyze at different velocities under any given set of hydrolytic conditions. Our invention contemplates also separations of entirely different character which depend upon whether the initial sulfonation was carried out at a relatively low or a relatively high temperature.

20 The extraction of the free phenols from the unhydrolyzed sulfonic acids may be carried out in any suitable manner, for example, in a batch agitator or in a continuous countercurrent extraction column.

25 The solvent employed should preferably have a boiling point sufficiently different from the boiling point of the alkyl phenols extracted to enable their separation without requiring a high degree of fractionation. The solvent should be substantially immiscible with water and thermally and chemically stable under the conditions of the process. Examples of suitable solvents are benzene, toluene, xylene, kerosene, gasoline and other aromatic or paraffinic hydrocarbon fractions of suitable boiling range, chlorinated hydrocarbons, such as carbon tetrachloride, carbon disulfide, oxyhydrocarbon solvents such as ketones, ethers, esters, monohydric alcohols, etc., which are substantially water-immiscible.

30 It is preferable to carry out the hydrolytic step in the presence of a portion of solvent. The solvent dissolves the phenols as they are freed and thus tends to remove them from the reaction, thereby favorably affecting the equilibrium to encourage further hydrolysis. In general, we prefer to carry out the hydrolysis in the presence of from 0.5 to 10 parts of solvent per part of mixture.

35 The length of time during which the mixture to be hydrolyzed is maintained under the conditions of hydrolysis depends upon the particular separation in question. However, we have found that suitable times generally are from $\frac{1}{4}$ to 50 hours, and must be determined by experience for any given separation.

Example I

40 70 75 200 grams of a fraction of petroleum alkyl phenols boiling from 215-220° C. and known to be saturated with 2,4,6-trimethyl phenol at 0° C. was sulfonated with 153 grams of 97% sulfuric acid. The resulting mixture of sulfonic acids and alkyl phenols was diluted with 232 grams of water and extracted once with 100 cc. and once

with 50 cc. of benzene. The benzene extracts, which contained only traces of sulfonic acids, were washed with a dilute solution of sodium bicarbonate and then distilled to recover the alkyl phenols contained in them. These were found to amount to about 25% of the charge and contained so much 2,4,6-trimethyl phenol that considerable amounts of it crystallized from the liquid at room temperature. The 2,4,6-trimethyl phenol recovered upon filtration of the mixture amounted to 25 grams.

Example II

500 grams of a fraction of petroleum alkyl phenols boiling from 225-240° C., and known to contain less than 5% of 2,3,5-trimethyl phenol, was sulfonated with 376 grams of 97% sulfuric acid. The mixture of alkyl phenols and sulfonic acids was diluted with 600 grams of water and extracted once with 250 cc. and once with 125 cc. of benzene. The benzene extracts, which contained considerable amounts of alkyl phenols, were washed with sodium bicarbonate solution to remove the traces of sulfonic acids present, following which the benzene was distilled off and the alkyl phenols recovered. Upon fractional distillation of these unsulfonated phenols a fraction, amounting to 50 grams, which contained 32% of 2,3,5-trimethyl phenol, was recovered. The 2,3,5-trimethyl phenol precipitated out of this mixture at room temperature and 10 grams of the pure substance was recovered by filtering.

Another portion of the original mixture was subjected to a fractional distillation under conditions similar to those employed with the unsulfonated fraction. However, under these conditions it was not possible to obtain a fraction which contained a sufficient concentration of 2,3,5-trimethyl phenol to cause any of that substance to precipitate out of solution.

Example III

A mixture containing 100 grams of 2,5-dimethyl phenol sulfonic acid and 100 grams of 2,6-dimethyl phenol sulfonic acid in solution in 300 grams of 50% sulfuric acid was heated at 100° C. for 20 hours. At the end of this period, the reaction mixture was cooled and extracted with a portion of toluene. The toluene was washed with sodium bicarbonate solution to remove traces of sulfuric acid and sulfonic acid and then distilled off to leave a residue of about 50 grams of almost pure 2,5-dimethyl phenol. Since the hydrolysis of 2,6-dimethyl phenol sulfonic acid in 50% sulfuric acid is very slow at 100° C., the temperature of the residual liquid was raised to 125° C. for an additional ten hours. At the end of this period, the reaction mixture was cooled and extracted with toluene. Following the usual washing of the extract phase, the toluene was distilled off to leave a residue of 60 grams of 80% pure 2,6-dimethyl phenol.

It is clear that if the first period of heating had been some what longer then the 2,5-dimethyl phenol recovery would have been larger, but its purity would have been less; there would be an accompanying diminution in yield and increase in purity of the 2,6-dimethyl phenol. Actually, while such modifications of the process could be carried to absurdity, an addition of ten hours to the first period of hydrolysis would have increased the yield of 2,5-dimethyl phenol to about 58 grams and would have resulted in the simultaneous hydrolysis of only about 2 grams more of 2,6-dimethyl phenol.

Example IV

15 A mixture of 100 grams of 2,4-dimethyl phenol sulfonic acid and 100 grams of 2,5-dimethyl phenol sulfonic acid in solution in 300 grams of 50% aqueous sulfuric acid was heated at 100° C. for three hours. At the end of this period, the reaction mixture was extracted with toluene and the toluene phase washed to remove small amounts of sulfuric and sulfonic acids. The alkyl phenols which were recovered by distillation of the extract phase amounted to 50 grams and contained 75% of 2,4-dimethyl phenol. If the hydrolysis were carried out at lower temperatures, the separation would be even better, although the time required would be much longer. At higher temperatures, the separation is poorer and, in the neighborhood of 115-125° C., the relative rates of hydrolysis are reversed, the 2,5-dimethyl phenol sulfonic acid being more rapidly hydrolyzed than the 2,4-dimethyl phenol sulfonic acid.

35 We claim as our invention:

1. A process for separating a mixture of alkyl phenols comprising the steps of sulfonating said mixture under conditions to favor monosulfonation, adding water and a substantially water-immiscible solvent to the resulting alkyl phenol monosulfonic acids, maintaining the resulting mixture under conditions favorable to hydrolysis until a part of said sulfonic acids has hydrolyzed, then extracting the resulting mixture with said solvent to form a solvent phase containing dissolved alkyl phenols and a residual phase containing alkyl phenol monosulfonic acids, and subsequently hydrolyzing the residual sulfonic acids to regenerate the corresponding phenols.

40 2. The process of claim 1 wherein the sulfonation is carried out at a temperature between about 0° C. and 150° C. with sulfuric acid in an amount of from about one to 5 equivalents of sulfuric acid per equivalent of alkyl phenols in the mixture, and wherein the amount of solvent added with the water is from .5 to 10 parts of solvent per part of the mixture.
